CLAIM

The ornamental design for a coupon and shopping list holder, as shown and described.

DESCRIPTION

FIG. 1 is a right side, top and front perspective view of a coupon and shopping list holder showing my new design, the fragmentary shopping cart depicted by means of broken lines being shown for illustrative purposes only and forming no part of the claimed design;

FIG. 2 is a front elevational view thereof;

FIG. 3 is a right side elevational view thereof;

FIG. 4 is a top plan view thereof;

FIG. 5 is a rear elevational view thereof; and,

FIG. 6 is a bottom plan view thereof.
